UNITED STATES PATENT OFFICE

2,244,880

AUTOMATIC PROGRESSIVE CONTROL SYSTEM

Curtis L. Howse, Birmingham, Mich., assignor to
 Diamond Power Specialty Corporation, Detroit, Mich., a corporation of Michigan

Application October 26, 1939, Serial No. 301,516

14 Claims. (Cl. 172—239)

This invention relates to control systems for electrically powered work performing units and has for its primary object to provide a system which automatically operates a multiplicity of independent units successively and in definite sequence.

The invention has particular utility in conjunction with soot blower units which are used for the purpose of cleaning the tubes and other parts of boilers. Such units usually include an element insertable into the boiler and means for rotating said element and for controlling the supply thereto of steam, air or whatever other cleaning medium that might be used. This system, when used with soot blower units, provides for the successive operation of any number of blower units located any distance apart.

Another object of the invention is to provide a system of this character which is comparatively simple and therefore free from trouble such as results from the use of complicated control apparatus. In this respect the invention provides for the convention of the plurality of units by only two wires, and causes the units to operate successively according to the sequence in which they are connected along these two wires.

Another object is to provide a system of this character which automatically operates a signal device when the multiplicity of units have been successively operated.

Another object is to provide a system having means which automatically operates after the last of the successively operated units has been operated to render the entire system inoperative, and to restore it to its original state in order that the same cycle may be repeated.

With the above and other ends in view the invention is more fully disclosed with reference to the accompanying drawing, in which

Fig. 1 is a diagram of the system, and

Fig. 2 is a fragmental view of a soot blower unit.

For purposes of explanation a soot blower unit is shown in Fig. 2, the unit being of a type similar to that shown and described in United States Patent No. 1,809,221, to which attention is invited for a more complete understanding of the operation of the unit. It will be understood, of course, that the invention may be used in conjunction with various other types of soot blowers and this particular unit is illustrated by way of example only. It is not intended that the chosen illustration should be construed as limiting the invention to this particular use.

Briefly described, the soot blower unit com-

prises a supply pipe 1 connected to a valve chamber 2 in which is mounted a valve 3 for controlling the flow of cleaning fluids from the pipe 1 through a conduit 4 to an element 5. The element 5 is adapted to be inserted into a boiler. A motor 6, through a speed reducing gear 7, operates a gear 8 which is fixed on the element 5 for rotation thereof, and which carries a cam 9 for operating the valve. The cycle of operation of the unit is controlled by the gear 8 inasmuch as the valve 3 is opened and closed with each operation thereof.

The system hereinafter described is designed to control the operation of a multiplicity of units such as above described so that when one unit completes a cycle of operation, equivalent to one rotation of the gear 8, it is rendered inoperative and the next unit in the series is rendered operative. The same operation takes place in connection with each unit until all of the units have been operated successively.

Fig. 1 illustrates three units, A, B and C, although the number might be two units or it might be increased to any reasonable number. In these units, the motor 6 and gears 7 and 8 correspond to the parts bearing similar reference characters in Fig. 2. The several units are identical and, therefore, the reference characters hereinafter employed refer to similar parts in all of the units.

Power is supplied for operating the several units by the main line wires L and G which through a starting switch 10 are adapted to be connected to the wires L₁ and G₁. The wire L₁ extends to the motor 6 of the first unit A and has a switch gap 11 therein which is normally closed by a switch member 12 having an electro-magnetic coil and armature assembly 13 for moving the switch member to open the gap 11. The motor is also connected by a wire 14 to the wire G₁ and it will be observed that upon closing of the switch 10 the motor 6 is in circuit with the main line wires L and G.

The circuit for the electro-magnet 13 comprises a wire 15, connected to the wire L₁ between the switch gap 11 and the motor 6, a normally open single pole switch 16 connected by a wire 17 to the electro-magnet 13, and a wire 18 connecting the electro-magnet 13 to the line G₁.

With the motor 6 operating as above described the gear 8 is caused to rotate. On the gear 8 is a cam or lug 24 which, after one revolution of the gear 8 in a clockwise direction, closes the single pole switch 16 and thereby closes the circuit of the electro-magnet 13. The switch member 12 is

pulled from contact with the gap terminals 11 by the electro-magnet, and thereby opens the circuit of the motor 6 and ordinarily would immediately suspend operation thereof. However, as will hereinafter appear, the motor circuit is only momentarily broken at this particular stage in the operation.

Two switch gap terminals 20 and 21 are engaged by the switch member 12 as a result of operation of the magnet 13 as above described. It will be noted, in this respect, that the circuit to the electro-magnet 13 is opened when the switch member moves from engagement with the gap terminals 11. However, the motion given the armature of the electro-magnet before the circuit is entirely broken as well as the inertia of the magnetic forces will carry the switch 12 into contact with the terminals 20 and 21.

The switch terminal 20 is electrically connected by the wire 22 to the wire 17 and the terminal 21 is connected by a wire L₂ to the wire L₁. Therefore, when the terminals 20 and 21 are bridged by the switch member 12 the electro-magnet 13 is again energized. It will also be noted that while the switch 16 is closed and the terminals 20 and 21 bridged, current may flow from the wire L₁, wire 22, switch 16, wire 15 and wire L₁ to the motor. Therefore, the motor continues to operate until the cam 24 passes the switch 16 and allows the switch to open, thus making it impossible for the cam to stop in a position holding the switch 16 closed.

The terminal 20 of the first unit A is connected by a wire L₃ to the motor of the second unit B, in which unit the system is identical to that above described and where like reference characters apply with the single exception of L₄ which designates the wire leading from the switch terminal 20 of the unit B to the motor of the unit C. In other words, the wires L₁ of unit A, L₃ of unit B and L₄ of unit C have identical relationship with their respective units.

It becomes apparent, therefore, that when the switch 16 of the unit A is operated it results in opening of the motor circuit in its unit and closing of the motor circuit in the unit B, and when the switch 16 of the unit B is operated it causes the motor circuit of its unit to be opened and causes closing of the circuit of the motor in the unit C. Any reasonable number of units may be arranged in series in this manner.

It is desirable, of course, to provide means for indicating completion of the operation of all the units or for automatically opening the switch 16 to suspend operation until such time as repetition of the operation might be desired. The invention provides for both.

The indicator 21 is connected by a wire L₅ to the terminal 20 of the unit C and to the wire G₁. Therefore, when the line L₅ is energized at the completion of the operation of the unit C the indicator 21 is operated.

To open the switch 16 after the final unit has operated and before the first unit can operate again, an electro-magnet 22 is connected to the switch 16 and is operated by closing of the switch 23. The switch 23, which is also electrically operated, is connected to the wire L₅ and the wire G₁ so that it operates when the switch member 12 of the unit C bridges the contacts 20 and 21 of the unit C.

When the starting switch 16 is opened all of the electrically operated switches return to their normal or non-energized positions, and re-closing

of the starting switch will again cause each unit to repeat its cycle of operation.

What is claimed is:

- 5 1. In combination, a series of electrically operated units, each unit having an energizing circuit, a starting switch for rendering the energizing circuit of the first unit operative, each unit having control means operable at a predetermined stage in the cycle of its operation for de-energizing its energizing means and for rendering the energizing means of the next unit in the series operative, and means rendered operative by said control means in the final unit for opening said starting switch.
- 10 2. In combination, a series of electrically operated units, a circuit for the first unit including a starting switch and a second switch having electrically-operated means for opening the same and yielding means normally holding it closed, a circuit for said electrically operated switch operating means subject to opening thereof by opening of said second switch and also having a third switch, means normally holding said third switch open, means operating in timed relation to the operation of the first unit for closing said third switch to operate said electrically-operated switch operating means to open said second switch, a circuit having a control operated by and adapted to be closed by operation of said electrically-operated switch operating means, said last-named circuit being connected to the next unit in the series and through the third switch when closed to the first unit of the series whereby the first unit is energized through the last named circuit until it passes the stage where it closes the third switch.
- 15 3. In combination, a series of electrically operated units, a circuit for the first unit including a starting switch and a second switch having yielding means normally holding it closed and electrically-operated means for opening the same, a circuit for said electrically operated switch operating means subject to opening of the second switch by operation of the electrically-operated switch operating means and also having a third switch, means normally holding said third switch open, means operating in timed relation to the operation of the first unit for closing said third switch to operate said electrically-operated means and open said second switch, a circuit having a control adapted to be closed by operation of said electrically-operated means, said last-named circuit being connected to the next unit in the series and through the third switch to the first unit of the series whereby the first unit is energized through the last named circuit until it passes the stage where it closes the normally open switch, said last named circuit also being connected to said electrically-operated means for energizing the same to maintain the second in its open position.
- 20 4. In combination, a series of electrically operated units, a circuit for the first unit including a starting switch and a second switch having yielding means normally holding it open and electrically-operated means for operating the same, a circuit for said electrically operated switch operating means subject to opening of the second switch by operation of the electrically-operated switch operating means and also having a third switch, means normally holding said third switch open, means operating in timed relation to the operation of the first unit for closing said third switch to operate and open said electrically-operated means to close said second switch.

a circuit having a control adapted to be closed by operation of said electrically-operated means, said last named circuit being connected to the next unit in the series and through the third switch to the first unit of the series whereby the first unit is energized through the last named circuit until it passes the stage where it closes the third switch, and means operated by the last named circuit of the final unit for opening said starting switch.

5. In combination, a series of electrically operated units, a first circuit for each unit for energizing each unit, the first circuit of the first unit having a starting switch and the first circuit of each unit having a second switch operable to open the first circuit of its respective unit and to close the first circuit of the next unit in the series, means normally holding each of the second switches closed, each of said second switches having an electro-magnet for opening the same, the first circuit of each unit being connected to the electro-magnet of its second switch by a second circuit which is opened by opening of the second switch and which also includes a third switch, means normally holding each third switch open, and means operated in cyclic relation with the operation of each unit for closing the third switch of the second circuit.

6. In combination, a series of electrically operated units, a first circuit for each unit for energizing each unit, the first circuit of the first unit having a starting switch and the first circuit of each unit having a second switch operable to open the first circuit of its respective unit and to close the first circuit of the next unit in the series, means normally holding each of the second switches closed, each of said second switches having an electro-magnet for opening the same, the first circuit of each unit being connected to the electro-magnet of its second switch by a second circuit which is opened by opening of the second switch and which also includes a third switch, means normally holding each third switch open, means operated in cyclic relation with the operation of each unit for closing the third switch of the second circuit, and means operated by closing of the second circuit of the final unit of the series for opening said starting switch.

7. In combination, a series of electrically operated units, a first circuit for each unit for energizing each unit, the first circuit of the first unit having a starting switch and a second switch operable to disconnect the first circuit from its respective unit and to connect it with the first circuit of the next succeeding unit in the series, means normally holding the second switch closed, a second circuit controlled by said second switch, said second circuit having a third switch therein and an electro-magnet for operating said normally closed switch, means normally holding said third switch closed, and means operating in timed relation to the operation of each unit for closing the third switches of respective units.

8. In combination, a series of electrically operated units, a first circuit for each unit for energizing each unit, the first circuit of the first unit having a starting switch and a second switch operable to disconnect the first circuit from its respective unit and to connect it with the first circuit of the next succeeding unit in the series, means normally holding said second switch closed, a second circuit controlled by said second switch, said second circuit having a third switch therein and an electro-magnet for operating said second

switch, means operating in timed relation to the operation of each unit for closing respective third switches, and a third circuit connected to the first circuit of each of the succeeding units of the series, each third circuit being connected through the third switch of the unit which it succeeds to the unit to cause operation of the unit while said third switch is closed.

9. In combination, a series of electrically operated units, a first circuit for each unit for energizing each unit, the first circuit of the first unit having a starting switch and a second switch operable to disconnect the first circuit from its respective unit and to connect it with the first circuit of the next succeeding unit in the series, means normally holding said second switch closed, a second circuit controlled by said second switch, said circuit having a third switch therein and an electro-magnet for operating said second switch, means normally holding said third switches open, means operating in timed relation to the operation of each unit for closing respective third switches, and means for automatically opening said starting switch at the completion of the cycle of the final unit.

10. In combination, a series of electrically operated units, a first circuit for each unit for energizing each unit, the first circuit of the first unit having a starting switch and a second switch operable to disconnect the first circuit from its respective unit and to connect it with the first circuit of the next succeeding unit in the series, means normally holding said second switch closed, a second circuit controlled by said second switch, said circuit having a third switch therein and an electro-magnet for operating said second switch, means normally holding said third switch open, means operating in timed relation to the operation of each unit for closing respective third switches, a third circuit connected to the first circuit of each of the succeeding units of the series, each third circuit being connected through the third switch of the unit which it succeeds to the unit to cause operation of the unit while said third switch is closed, and means for automatically opening said starting switch at the completion of the cycle of the final unit.

11. In combination, a series of electrically operable units, wherein each unit embodies a movable part having cyclic relationship with the operation of the unit, and wherein each unit embodies an operating motor, a pair of main line wires, one of said main line wires being connected through a starting switch to the motor of each unit, the other of said main line wires being connected through said starting switch to the motor of the first unit by a circuit including a second switch, means normally holding said second switch closed, each succeeding unit having a circuit including a switch corresponding to said second switch, each second switch being operable to open its respective circuit and to close the circuit of the next succeeding unit, a magnet for opening each second switch, said magnet being connected through said second switch to the first named circuit of its respective unit by a circuit including a third switch, means normally holding each third switch open, and means on said movable part for closing the third switch of its respective unit.

12. In combination, a series of electrically operable units, a first circuit for the motor of the first unit, means normally closing said first circuit, a circuit dependent on the first circuit and having a circuit control for opening the first

circuit, means normally opening said second circuit, means operated at a predetermined stage in the operation of the first unit for closing the second circuit to cause it to open the first circuit, a third circuit for energizing said motor through the closed second circuit to operate said motor past the stage where said second circuit was closed, and a fourth circuit connected to the first circuit by operation of said circuit control, said fourth circuit being the first circuit of the next succeeding unit of the series.

13. In combination, a series of electrically operable units, a first circuit for the motor of the first unit, means normally closing said first circuit, a circuit dependent on the first circuit and having a circuit control for opening the first circuit, means normally opening said second circuit, means operated at a predetermined stage in the operation of the first unit for closing the second circuit to cause it to open the first circuit, a third circuit for energizing said motor through the closed second circuit to operate said motor past the stage where said second circuit was closed, a fourth circuit connected to the first circuit by operation of said circuit control, said fourth circuit being the first circuit of the next succeeding

unit of the series, and means operated by the fourth circuit of the final unit for rendering the entire series inoperative.

14. In combination, a series of electrically operated units, a pair of main line wires, means including a starting switch for connecting one of said main line wires with each unit, a circuit having a switch gap connecting the other main wire to the first unit through said starting switch, a switch member closing said switch gap and having an electro-magnet for moving the same to open said gap, a second circuit for energizing the electro-magnet comprising a wire connected to the first circuit between the switch gap and the unit, said second circuit having an open switch and a connection with the first of said main line wires, means operating in timed relation to the operation of the first unit for closing said open switch whereby the first unit and the electro-magnet are de-energized, and a third circuit connected to said electro-magnet and through the second circuit switch when closed to the motor for re-energizing the magnet and for operating the first unit past the stage where it closed said second circuit switch.

CURTIS L. HOWSE.
